CLAIM

The ornamental design for an electric faucet, as shown and described.

DESCRIPTION

FIG. 1 is a front perspective view of an electric faucet showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The evenly broken lines represent parts of the article that form no part of the claimed design. The dot-dash lines represent the boundaries of the claim and form no part thereof.

1 Claim, 7 Drawing Sheets(56)
